(57) **CLAIM**

The ornamental design for a combined dispenser and receptacle of consumables, as shown and described.

DESCRIPTION

FIG. 1 is a front perspective view of a combined dispenser and receptacle of consumables according to a first embodiment, shown with the receptacle in a receiving position.

FIG. 2 is a rear perspective view of the combined dispenser and receptacle of consumables of FIG. 1, shown with the receptacle in the receiving position.

FIG. 3 is a front view of the combined dispenser and receptacle of consumables of FIG. 1, shown with the receptacle in the receiving position.

FIG. 4 is a left side view of the combined dispenser and receptacle of consumables of FIG. 1, shown with the receptacle in the receiving position.

FIG. 5 is a right side view of the combined dispenser and receptacle of consumables of FIG. 1, shown with the receptacle in the receiving position.

FIG. 6 is a top view of the combined dispenser and receptacle of consumables of FIG. 1, shown with the receptacle in the receiving position.

FIG. 7 is a bottom view of the combined dispenser and receptacle of consumables of FIG. 1, shown with the receptacle in the receiving position.

FIG. 8 is a back view of the combined dispenser and receptacle of consumables of FIG. 1, shown with the receptacle in the receiving position.

(Continued)

FIG. 9 is a front perspective view of the combined dispenser and receptacle of consumables of FIG. 1, shown with the receptacle in a position away from the receiving position. FIG. 10 is a rear perspective view of the combined dispenser and receptacle of consumables of FIG. 1, shown with the receptacle in the position away from the receiving position. FIG. 11 is a front view of the combined dispenser and receptacle of consumables of FIG. 1, shown with the receptacle in the position away from the receiving position. FIG. 12 is a left side view of the combined dispenser and receptacle of consumables of FIG. 1, shown with the receptacle in the position away from the receiving position. FIG. 13 is a right side view of the combined dispenser and receptacle of consumables of FIG. 1, shown with the receptacle in the position away from the receiving position. FIG. 14 is a top view of the combined dispenser and receptacle of consumables of FIG. 1, shown with the receptacle in the position away from the receiving position. FIG. 15 is bottom view of the combined dispenser and receptacle of consumables of FIG. 1, shown with the receptacle in the position away from the receiving position. FIG. 16 is a front perspective view of the receptacle, shown separately from the dispenser to reveal aspects of the receptacle not visible in other views. FIG. 17 is rear perspective view of the receptacle, shown separately from the dispenser to reveal aspects of the receptacle not visible in other views. FIG. 18 is a top view of the receptacle, shown separately from the dispenser to reveal aspects of the receptacle not visible in other views. FIG. 19 is a left side view of the receptacle, shown separately from the dispenser to reveal aspects of the receptacle not visible in other views. FIG. 20 is a front view of the receptacle, shown separately from the dispenser to reveal aspects of the receptacle not visible in other views. FIG. 21 is a right side view of the receptacle, shown separately from the dispenser to reveal aspects of the receptacle not visible in other views. FIG. 22 is a back view of the receptacle, shown separately from the dispenser to reveal aspects of the receptacle not visible in other views. FIG. 23 is a bottom view of the receptacle, shown separately from the dispenser to reveal aspects of the receptacle not visible in other views. FIG. 24 is a front perspective view of a combined dispenser and receptacle of consumables according to a second embodiment. FIG. 25 is a rear perspective view of the combined dispenser and receptacle of consumables of FIG. 24. FIG. 26 is a front view of the combined dispenser and receptacle of consumables of FIG. 24. FIG. 27 is a left side view of the combined dispenser and receptacle of consumables of FIG. 24. FIG. 28 is a right side view of the combined dispenser and receptacle of consumables of FIG. 24. FIG. 29 is a top view of the combined dispenser and receptacle of consumables of FIG. 24. FIG. 30 is a bottom view of the combined dispenser and receptacle of consumables of FIG. 24; and, FIG. 31 is a back view of the combined dispenser and receptacle of consumables of FIG. 24.

The broken lines shown in the drawings illustrate portions of the combined dispenser and receptacle of consumables that form no part of the claimed design.
